ABSTRACT OF THE DISCLOSURE

A gas blast circuit breaker comprising separable contacts for establishing an arc that is transferred to spaced-apart electrodes. A main gas blast extending axially of the arc is developed during both low and high current interruptions. During high current interruptions there is also developed an auxiliary blast that flows through the upstream electrode. This auxiliary blast is initiated by electroresponsive means responsive to overcurrents through the contacts even before the arc is initiated. The electroresponsive means remains inactive during low current interruptions, and no auxiliary blast is developed during low current interruptions.

Background of the invention

This invention relates to a gas blast circuit breaker and, more particularly, to means for improving the interrupting ability of such a circuit breaker.

The usual gas blast circuit breaker comprises means for establishing an electric arc across the gap between two electrodes and means for directing a high velocity blast of gas into the arcing region. The purpose of this blast is to cool the arc and to scavenge the arcing region of arcing products so as to increase the rate at which dielectric strength is built up across the gap when the current zero point is reached. By increasing the rate of dielectric recovery, it is possible to improve the ability of the gap to withstand the usual recovery voltage transient that builds up as soon as current zero is reached, thus improving the interrupting ability of the circuit breaker.

A common type of gas blast circuit breaker is the axial blast type. In such a breaker, the blast of gas flows axially of the arc, first passing the one electrode which is normally referred to as the upstream electrode and then passing the other electrode, which is referred to as the downstream electrode. It has been found that the interrupting capacity of the axial blast type circuit breaker can be increased by providing an auxiliary blast passage in the upstream electrode and by directing an auxiliary blast from the arcing region through the auxiliary blast passage during interruption. But it has been found also that the ability of such a circuit breaker to interrupt capacitive currents which typically are only several hundred amperes or less, is impaired by such an auxiliary blast.

Summary

Accordingly, an object of my invention is to provide simple, reliable, high-speed control means which can produce an auxiliary gas blast from the arcing region through the upstream electrode for high current interruptions and yet does not detract from the ability of the breaker to interrupt capacitive currents.

Another object is to provide control means of this type which can open an auxiliary blast valve before the main blast valve opens and before the contacts part during a circuit interrupting operation.

Another object is to provide control means of this gen-

eral type which effects closing of the auxiliary blast valve immediately after a circuit-interrupting operation, thereby preventing waste of pressurized gas.

In carrying out my invention in one form, I provide a pair of contacts through which current passes when the circuit breaker is closed, the contacts being separable to initiate an arc therebetween. Adjacent the contacts is a pair of spaced electrodes onto which the arc is transferred. Means is provided for causing a main blast of gas to pass axially of the arc during both high and low current interruptions. An auxiliary blast passage extends through the electrode located upstream from the arc with reference to said main blast. A normally-closed auxiliary blast valve is provided for controlling flow through said auxiliary blast passage and is openable to produce an auxiliary blast from said arcing region through said auxiliary blast passage. The auxiliary blast valve is controlled by electroresponsive means responsive to overcurrents through said contacts even before said arc is initiated for opening said auxiliary blast valve during high current interruptions. Means is provided for maintaining said auxiliary blast valve closed during low current interruptions.

Brief description of drawings

For a better understanding of the invention, reference may be had to the following description taken in conjunction with the accompanying drawings, wherein:

FIG. 1 is a sectional view through a circuit breaker embodying one form of my invention.

FIG. 2 is a sectional view of a portion of FIG. 1.

FIG. 3 is a sectional view along the line 3—3 of FIG. 2.

Detailed description of preferred embodiment

Referring now to FIG. 1, the circuit interrupter shown therein is of the sustained-pressure, gas-blast type described and claimed in U.S. Patent 2,783,338, Beatty, assigned to the assignee of the present invention. Only those parts of the interrupter that are considered necessary to provide an understanding of the present invention have been shown in FIG. 1. In this respect, only the right hand portion of the interrupter has been shown in section inasmuch as the interrupter is generally symmetrical with respect to a vertical plane and the left hand portion is substantially identical to the right hand portion. As described in detail in the above-mentioned Beatty patent, the interrupter comprises a casing 12 which is normally filled with pressurized gas to define an interrupting chamber 11. Located within the interrupting chamber 11 are a pair of relatively movable contacts 14 and 16 which can be separated to draw an arc within the pressurized gas within the chamber 11. The contact 14 is relatively stationary, whereas the other contact 16 is mounted for pivotal motion about a fixed, current-carrying pivot 18. Stationary contact 14 is mounted on the inner end of a high voltage terminal bushing 7 comprising two porcelain shells 8 and 8a and a conductive stud 9 extending therethrough. When movable contact 16 is driven clockwise about pivot 18 from its solid-line closed position of FIG. 1, an arc is established in the region where the contacts part. The movable contact 16 is shown by dotted lines in FIG. 1 in a partially-open position through which it passes during a circuit-interrupting operation after having established an arc.

Movable contact 16 is supported by means of its current-carrying pivot 18 on a conductive bracket 19 that is preferably formed integral with a stationary cylinder 32. Cylinder 32 at its lower end is suitably supported from a generally cylindrical casting 33. Casting 33 at its

lower end is suitably secured to a flange 35 rigidly carried by the stationary metallic casting 12.

For producing a gas blast to aid in extinguishing the arc, cylindrical casting 33 contains a normally-closed exhaust passage 36 leading from the interrupting chamber 11 to the surrounding atmosphere. Casting 33 at its upper end is provided with a tubular nozzle member 38 having an orifice portion 39 at its outer end defining an inlet 37 to the exhaust passage 36. This inlet 37 is referred to hereinafter as the orifice opening. The flow of arc-extinguishing gas through tubular nozzle 38 and exhaust passage 36 is controlled by means of a cylindrically-shaped reciprocable blast valve member 40 located at the outer, or lower, end of exhaust passage 36. This blast valve member 40 normally occupies a solid-line, closed position wherein a portion 42 at its lower end sealingly abuts against a stationary valve seat 34 carried by exhaust casting 33.

During a circuit interrupting operation, movable blast valve member 40 is driven upwardly from its solid-line, closed position of FIG. 1 through a partially open intermediate position shown in dotted lines in FIG. 1. Opening of valve member 40 allows pressurized gas in the chamber 11 to flow at high speed through orifice opening 37 and nozzle 38 and out exhaust passageway 36 past valve member 40 to atmosphere, as indicated by the dotted line arrows B of FIG. 1. The manner in which the gas blast acts to extinguish the arc will soon be described in greater detail.

At its upper end, the cylindrical blast valve member 40 surrounds a projecting cylindrical support 41 upon which the valve member 40 is smoothly slidably. The support 41 is fixed to the casting 33 by suitable means (not shown). A suitable compression spring (not shown) positioned between the movable valve member 40 and the lower end of support 41 tends to hold the valve member 40 in its closed position against the valve seat 34.

To protect support 41 and the upper end of valve member 40 from the harmful effects of arcing, a protective metallic tube 43 is positioned about these parts and is suitably secured to support 41. Secured to the outer surface of this tube is a downstream probe or electrode 45, preferably of a refractory metal, which projects radially from tube 43 and transversely into the path of the gas blast flowing through passageway 36. As will soon appear more clearly, the downstream terminal of the arc is transferred to this electrode 45 during an interrupting operation and, after such transfer, occupies an instantaneous position generally corresponding to that shown at 46. The downstream electrode is preferably constructed as shown and claimed in Patent No. 2,897,324, Schneider, assigned to the assignee of the present invention, so that it has a nonstreamlined upstream surface 48 that coacts with the gas blast to form a stagnation region upstream from the surface 48. The terminal of an arc such as 46 reaching the electrode 45 is captured within the stagnation region and thus prevented from being driven further downstream by the gas blast.

For controlling the operation of movable blast valve 40 and movable contact 16, a combined operating mechanism 50 is provided. This mechanism 50 is preferably constructed in the manner disclosed and claimed in the aforementioned Beatty Patent 2,783,338, and its details form no part of the present invention. Generally speaking, this mechanism 50 comprises a blast valve-controlling piston 51 and a contact-controlling piston 52 mounted within the cylinder 32. Blast valve-controlling piston 51 is coupled to movable blast valve member 40 through a piston rod 54 suitably clamped to valve member 40. The contact-controlling piston 52, on the other hand, is connected to the movable contact 16 through a piston rod 58 and a cross head 59 secured to the piston rod. A link 60 pivotally poined to the cross head 59 at 61 and to the movable contact 16 at 62 interconnects cross head 59 and movable contact 16. When blast valve-controlling

piston 51 is driven upwardly, it acts to open blast valve member 40, and, simultaneously, to drive contact-controlling piston 52 upwardly to produce opening movement of the movable contact member 16.

Opening movement of contact member 16 first establishes an arc between the ends of the contacts 14 and 16. Shortly thereafter, however, the blast of gas which has been flowing through the orifice opening 37, as indicated by the dotted-line arrows B, forces the upstream terminal of the arc on to an upstream arcing electrode 70, which is electrically connected to the stationary contact 14. As opening motion of movable contact 16 continues, the gas blast forces the downstream terminal of the arc to transfer from the movable contact 16 to orifice structure 39, which is electrically connected to the movable contact 16. The gas blast then impels the downstream terminal of the arc through the orifice opening 37 and nozzle 38 on to the upper end of the protective metallic tube 43. From there, the gas blast drives the downstream arc terminal downwardly and into the previously-described stagnation region adjacent the upstream surface 48 of the electrode 45. The arc then occupies the position generally shown at 46. When the arc is in this position, the arc column extends through the orifice opening 37 and is subjected to the cooling and deionizing effect of the axial blast.

After completion of the interrupting operation, the blast valve 40 is returned to its closed position of FIG. 1 by the operating mechanism 50 while the contacts 14, 16 remain open.

It has been found that the circuit-interrupting capacity of the circuit breaker of FIG. 1 can be increased by directing an auxiliary blast from the arcing region through the upstream electrode during the circuit-interrupting operation. For accommodating this auxiliary blast, I provide an auxiliary blast passage 95, 96 leading through the upstream electrode 70 and the hollow stud 9 to atmosphere. The portion of this auxiliary blast passage that extends through electrode 70 is designated 95 and the portion extending through stud 9 is designated 96.

The auxiliary blast passage is normally closed by means of a normally-closed auxiliary blast valve 90 comprising a movable valve member 92 cooperating with a valve seat 93 in a partition 94. But under high current conditions, as will soon be described, the movable auxiliary blast valve member 92 is moved to the left to open the auxiliary blast valve 90. This permits high pressure air to flow through the auxiliary blast passage 95, 96 to atmosphere via the then-open auxiliary blast valve 90. The path of the auxiliary blast is indicated by the arrows 97 in FIG. 1.

The auxiliary blast passage is dimensioned so that a much smaller flow passes therethrough than through the main blast passage 36 (assuming that both blast valves are open). The entrance to the auxiliary blast passage 95, 96 is through a restricted orifice 98 in the upstream electrode 70 which is designed to produce sonic velocity in this region. The orifice 98 is the principal and controlling restriction in the auxiliary blast passage when the auxiliary blast valve is open.

For operating the movable valve member 92 of the auxiliary blast valve, I provide (as shown in FIG. 2) a piston 99 connected to the movable valve member and slidably mounted in a cylinder 100. A spring 101 acting upon piston 99 urges the valve member 92 toward open position, but piston 99 is normally held in the valve-closed position shown by pressurized air acting on its upper surface. This pressurized air is derived from the interior of tank 12 through a control conduit 102, 103.

For controlling the flow of pressurized air through conduit 102, 103, I provide a pilot valve schematically shown at 104. When the movable valve element 105 of pilot valve 104 is in its illustrated position, free communication is afforded between the pressurized tank 12 and cylinder space 107 above piston 99. But when the

movable valve member 105 is rotated counterclockwise by 90 degrees, cylinder space 107 is isolated from the pressurized tank and is instead connected to atmosphere through conduit 110. This dumps the pressurized air above piston 99 and permits spring 101 to drive piston 99 and valve member 92 upwardly, thereby opening the auxiliary blast valve 90.

To close the auxiliary blast valve 90, the pilot valve member 105 is rotated in an opposite direction, returning it to its position of FIG. 2. This reestablishes high pressure above piston 99, forcing it downward and carrying valve member 92 into its closed position of FIG. 1. The space beneath piston 99 is vented to atmosphere through passage 111, and therefore piston 99 can freely return to its closed position when high pressure air is supplied to cylinder space 107.

For controlling the movable pilot valve member 105, I provide electroresponsive operating means 115 which is responsive to the magnitude of the current through conductive stud 9. This operating means comprises a magnetized core 116 fixedly mounted around the stud 9. Referring to FIG. 3, core 116 has a gap 117 therein and an armature 118 is located near the gap. When the current through stud 9 exceeds a predetermined value, the flux density in the gap 117 becomes high enough to pull the armature 118 downwardly into the gap, thereby operating a linkage 120 that actuates pilot valve 104.

Referring to FIG. 2, linkage 120 comprises a bell crank 122 mounted on a stationary pivot 124 and having one arm pivotally connected to armature 118 and its other arm connected to movable pilot valve element 105. The connection to movable pilot valve element 105 is through an operating rod 125 that is pivotally connected at its opposite end to the movable pilot valve element 105 and the bell crank 122, respectively. A reset spring 127 normally holds the parts in the position of FIG. 2.

When the current through stud 9 exceeds a predetermined value, e.g., twice the continuous current rating of the circuit breaker, a sufficient downward magnetic force is developed on armature 118 to move it downwardly against the bias of spring 127. This pivots bell crank 122 counterclockwise, driving operating rod 125 to the left and rotating pilot valve member 105 counterclockwise into its venting position. The spring 101 responds by driving piston 99 and blast valve member 92 upwardly into open position, thereby opening the auxiliary blast valve 90 and producing the auxiliary blast through the upstream electrode.

Although the above-described auxiliary blast substantially improves the dielectric recovery rate for high currents, such as fault currents, it has been found through extensive study and tests that it detracts from the ability of the circuit breaker to switch capacitive currents, which typically are only several hundred amperes or less. As explained in U.S. Patent 2,391,672, Boehne et al., assigned to the assignee of the present invention, interruption of such a current at current zero is followed by a relatively slow voltage buildup to a value approaching twice normal crest voltage. For some reason, not fully understood, the auxiliary blast appears to detract from the circuit breaker's ability to withstand this voltage, even though it substantially increases its ability to handle the much steeper voltage rises following current zero during the interruption of an inductive circuit of high currents. To improve the ability of the circuit breaker to handle capacitive currents, I control the auxiliary blast valve in such a manner that it opens only in response to relatively high currents, remaining closed for low currents, as described hereinabove. In a typical circuit breaker, I open the auxiliary blast valve only when the current exceeds about 5,000 amperes. Capacitive currents are typically only as high as several hundred amperes. So it will be evident that no auxiliary blast is established during capacitive switching operations. The operating current level for the auxiliary blast valve 90 is

established well above the continuous current rating of the circuit breaker so that the highest normal currents will not cause the auxiliary blast valve to open.

It is important that the auxiliary blast valve be opened rapidly during a high current interruption so that the auxiliary blast is available to aid in the arc-extinguishing process at the earliest possible moment. For a number of different reasons, my auxiliary blast valve is capable of opening within an extremely short time from the instant at which high current is initiated. One reason is that its moving parts are of a light-weight, low-mass construction, which construction is made possible, in part, because these components are not required to carry any of the current through the interrupter. This light-weight construction permits high speed motion. Another reason why my auxiliary valve can open quickly is that the valve-operating mechanism 115 can respond to the current flowing at all times through the interrupter. It is not necessary to draw an arc or to transfer the arc to some part of the interrupter before the valve-operating mechanism 115 can respond. It can respond immediately whether an arc is present or not since it responds to the current through stud 9, which represents the total current through the interrupter. Nor is the valve-operating means dependent upon a drop in tank pressure as a condition precedent to operation. Even if the main blast valve 40 is still closed and the pressure in tank 12 is at its normal high level, when the pilot valve 104 is operated, the spring 101 will produce opening of the auxiliary blast valve.

Nor does operation of the auxiliary blast valve depend upon some delicate balance between tank pressure and magnetic force, which could be detrimentally affected by a variation in tank pressure. In the illustrated arrangement, the operation of the pilot valve depends almost entirely on current level, and the operation of the auxiliary blast valve follows immediately thereafter with little dependence on normal tank pressure variations. Reclosing the auxiliary blast valve is likewise a positive operation which does not depend upon a delicate balance of tank pressure and magnetic force. As soon as the pilot valve 104 is returned to its position of FIG. 2 in response to a drop in current, a high positive force is available to reclose the auxiliary blast valve. The linkage 120 and reset spring 127 are so adjusted that reclosing of the auxiliary blast valve occurs at substantially the same current level at which the valve opened.

Another advantage of my auxiliary blast valve control is that it is a self-contained unit which requires no coupling to the main movable parts of the circuit breaker or to their controls. This not only contributes to simplicity but also eliminates electrical insulation problems which could arise from the presence of an additional insulating part (i.e., the coupling) subject to high voltage stress.

Sometimes it may be desired that the disclosed circuit breaker switch remain closed under fault current conditions while another circuit breaker, e.g., one further down the line, opens to clear the fault. It is recognized that passage of fault current through the illustrated circuit breaker will cause the auxiliary blast valve 90 to open even though the circuit breaker itself does not open. But this is not a significant disadvantage. The small amount of air consumed by opening of the small auxiliary blast valve is negligible since this opening continues for only a very short time inasmuch as the auxiliary blast valve closes as soon as the fault is removed by the other breaker.

While I have shown and described a particular embodiment of my invention, it will be obvious to those skilled in the art that various changes and modifications may be made without departing from my invention in its broader aspects; and I, therefore, intend in the appended claims to cover all such changes and modifications as fall within the true spirit and scope of my invention.

What I claim as new and desire to secure by Letters Patent of the United States is:

1. An electric circuit breaker of the gas blast type comprising:

- (a) a pair of contacts through which current passes when said circuit breaker is closed, said contacts being separable to initiate an arc therebetween, 5
- (b) a pair of spaced-apart electrodes onto which the respective terminals of said arc are transferred during an interrupting operation, 10
- (c) an orifice having an opening through which said arc is adapted to extend when present between said electrodes, 15
- (d) means for causing a main blast of gas to pass through said orifice opening axially of said arc about the arc periphery during both high and low current interruptions, 20
- (e) an auxiliary blast passage extending through the electrode located upstream from said orifice with reference to said main blast, 25
- (f) a normally-closed auxiliary blast valve for controlling flow through said auxiliary blast passage and openable to produce an auxiliary blast from the region of said arc through said auxiliary blast passage, 30
- (g) means responsive to current through said contacts above a predetermined value even before said arc is initiated for opening said normally-closed auxiliary blast valve during high current interruptions to produce an auxiliary blast through said auxiliary blast passage during high current interruptions, 35
- (h) and means for maintaining said auxiliary blast valve closed during low current interruptions.

2. The circuit breaker of claim 1 in which a conductive part is provided through which passes substantially all current flowing through said circuit breaker via either said contacts or said electrodes, said current-responsive means being controlled by the current passing through said conductive part.

3. An electric circuit breaker of the gas blast type 40 comprising:

- (a) a pair of contacts through which current passes when said circuit breaker is closed, said contacts being separable to initiate an arc therebetween, 45
- (b) a pair of spaced-apart electrodes onto which the respective terminals of said arc are transferred during an interrupting operation, 50
- (c) an orifice having an opening through which said arc is adapted to extend when present between said electrodes, 55
- (d) means for causing a main blast of gas to pass through said orifice opening axially of said arc about the arc periphery during both high and low current interruptions, 60
- (e) an auxiliary blast passage extending through the electrode located upstream from said orifice with reference to said main blast, 65
- (f) a normally-closed auxiliary blast valve for con-

trolling flow through said auxiliary blast passage and openable to produce an auxiliary blast from the region of said arc through said auxiliary blast passage,

- (g) an electroconductive part through which passes substantially all current passing through said circuit breaker via either said contacts or said electrodes, 65
- (h) a core mounted in close proximity to said electroconductive part and forming a magnetic circuit for flux developed by current passing through said electroconductive part, 70
- (i) means for opening said normally-closed auxiliary blast valve when the flux in said magnetic circuit reaches a predetermined density indicative of current through said conductive part reaching a predetermined value, 75
- (j) and means for maintaining said auxiliary blast valve closed during low current interruptions.
- 4. The circuit breaker of claim 3 in which the means for opening said normally-closed auxiliary blast valve comprises a pilot valve operable to effect opening of said auxiliary blast valve and means for operating said pilot valve when the flux in said magnetic circuit reaches said predetermined density.
- 5. The circuit breaker of claim 3 in which:

  - (a) said core is mounted about said electroconductive part and an armature is mounted nearby for movement in response to the flux reaching a predetermined density, and 80
  - (b) the means of limitation (i) comprises a linkage responsive to the motion of said armature.
  - 6. The circuit breaker of claim 3 in which:

    - (a) said core is mounted about said electroconductive part and an armature is mounted nearby for movement in response to the flux reaching a predetermined density, and 85
    - (b) the means of limitation (i) comprises a pilot valve connected to said armature and operable by motion of said armature for effecting opening of said auxiliary blast valve.
